B. C. ENGLISH AND FRANCIS FRAPS, OF SPRINGFIELD, MASSACHUSETTS.

Letters Patent No. 76,425, dated April 7, 1868.

IMPROVED SPRING-BED BOTTOM.

The Schedule referred to in these Letters Patent and making part of the same.

TO ALL WHOM IT MAY CONCERN:

Be it known that we, B. C. ENGLISH and FRANCIS FRAPS, of Springfield, Hampden county, Commonwealth of Massachusetts, have invented a new and useful Improvement in Spring-Beds; and we do hereby declare that the following is a full and clear description thereof, reference being had to the accompanying drawings, and to the letters of reference marked thereon. In the drawings—

Figure 1 is a side view, and

Figure 2 a plan view of our improvement.

This invention consists of a new and improved arrangement of slats and springs, whereby the bed is made strong, lasting, and elastic, and also adjustable. It is also applicable to lounges, sofas, and similar articles.

In construction, we form our bed of a number of frames, A A A, &c., set upon cross-bars B and B. These frames A each consist of a top and bottom slat, C and D, having springs E E, &c., between them, and being attached at their ends at F and F. The upper slat C is kept curved by the action of the springs E E, &c., and is fastened to the blocks G and G upon the ends of the slat D by means of screws a a. Rubber washers, b and b, are placed between the slat C and the top of the blocks G and G, at the points where the screws a and a connect them, the screws passing through them. These washers allow the slats to spring without loosening the screws, and also prevent them from creaking at their joints. The blocks G on each frame have holes d cut through them, so that the frames may be adjusted upon the rods B and B. Set-screws, f f, &c., are arranged in the blocks, and clamp the frames at each end upon the rods when screwed up, thus preventing them from getting displaced.

The advantages of this arrangement are, that a superior spring is obtained which is noiseless, adjustable, and lasting; it can be manufactured at a cost not greater than the average of bed-springs sold. The slats being adjustable upon the cross-rods, any number of them may be used that may prove most convenient.

Having described our invention, what we claim as new, and desire to secure by Letters Patent, is—

1. The double slat or frame A, consisting of top and bottom slats C and D, with springs E between them, and connected at their ends by means of the blocks G, screws a, and washers b, substantially as described.
2. The arrangement of the frames A upon cross-rods B and B, so as to be adjustable by set-screws f in the manner shown.

B. C. ENGLISH,
FRANCIS FRAPS.
